SHEET CONVEYER AND DELIVERY MECHANISM

Filed July 13, 1923

FIG. 1.

FIG. 2.

FIG. 3.

FIG. 4.

Inventor
RAYMOND S. DALTON.

Attorney

UNITED STATES PATENT OFFICE.

RAYMOND S. DALTON, OF CLEVELAND, OHIO, ASSIGNOR TO THE CLEVELAND FOLDING MACHINE COMPANY, OF CLEVELAND, OHIO, A CORPORATION OF OHIO.

SHEET CONVEYER AND DELIVERY MECHANISM.

Application filed July 13, 1923. Serial No. 651,216.

My invention relates to improvements in sheet conveyer and delivery mechanism and has for its object the provision of means for making an appliance such as the delivery table for supplying sheets of paper to folding and cutting machines more accurate and efficient than are those of the present development in the art. More particularly, my invention seeks to regulate in a novel 5 manner the advancement of the sheets upon the delivery table by constructing the rolls thereof so that they will have a varying effect for driving the sheets of paper at different areas or sections thereof in order to 10 counteract certain observed deficiencies in delivery tables now commonly in use.

The delivery table, presenting essentially a series of diagonally positioned rolls in association with a guide for one edge of the 20 sheet, has been known and used in the art for many years, associated with paper folding and cutting machines, ruling machines, printing presses of certain types, and the like. A common difficulty met with in the 25 employment of such machines, however, has been the conveying and delivery in proper position, of oblong sheets in the direction of their shorter dimension. A sheet of this character is found to be driven more rapidly from its free end than it is adjacent to its 30 guided edge, and, as a result, such sheet is liable to be turned upon the delivery table and thus will be presented in an indeterminate angular position to the folding rolls or the like. Makeshifts have been adopted 35 in the past to correct this undesirable tendency, found in the "drag" which may be applied to impede very slightly the tendency of the outer end or edge of the sheet to be 40 advanced faster than the guided edge. It is my present purpose to improve the structure of the delivery table so that this tendency will not be present and the sheets will be properly advanced to the associated 45 mechanism.

I have discovered that by increasing the driving or tractive effect of the rollers of a sheet delivery table, or some of said rollers, adjacent to the guided or slightly retarded 50 edge of the sheet, this undesirable tendency may be wholly counteracted and the efficiency of the delivery table is materially improved. This result may be accomplished by modifying the driving face of the rolls 55 throughout a portion of their length, as by

slightly roughening the surface thereof or by providing a slightly adherent surface. However, I preferably construct said rolls so that the diameters thereof, as presented toward the guiding edge of the delivery 60 table, shall be slightly greater than their diameters at a distance therefrom, or I may combine both principles of modifying the driving or tractive effect of such rolls.

This invention may further be explained, 65 as embodied in one type of delivery table of the class defined, by making reference to the accompanying drawings, wherein:

Figure 1 is a perspective view of a delivery table to which my improvements have 70 been applied,

Fig. 2 is a sectional view on line 2-2 of Fig. 1, partially diagrammatic in character for illustrating the drive for the rolls,

Fig. 3 is a view partially broken away and 75 in section showing one type of the preferred tubular roll with an enlarged end portion, and

Fig. 4 is a similar view showing a conical 80 type of roll.

Throughout the several figures of the drawings I have employed the same character of reference to indicate similar parts.

The structure of the delivery table shown 85 does not vary from those well known in the art and it may be taken as typical of any delivery table of this same general class, which may be modified in accordance with my present invention, but, as specifically embodied in the present mechanism, said delivery table comprises a frame *a* whereon are mounted a plurality of rolls or rollers *b* adapted to be driven in unison by an under-running belt *c* carried over idler rolls *d* positioned intermediately of the rollers *b*. 90 Said belt extends diagonally of the table and over the terminal pulleys, *c'*, *c''*, while adjustable tensioning rollers *c'*, *c''* permit the belt to be adjusted as required.

The sheets are fed to the delivery table 100 from the supporting shelf *e* and are successively advanced one by one toward the right by the rollers *b* which are rotated in a clockwise direction; coming promptly into engagement with the lefthand guide *f* prior to 105 their actuation beneath the roll *g*.

It will be observed that the rollers *b* are provided with frictioned and enlarged portions *b'* for a portion of their lengths; said frictioned and enlarged portions being dis- 110

posed immediately adjacent to the guide *f*. Alternatively the rollers may be knurled, as at *b*'' to insure an increased tractive effect, without increasing the diameter, or 5 otherwise suitably frictioned.

Another method of constructing these rolls is shown in Fig. 3, wherein the tubular body *h* of the roller is slightly flared or expanded for a short distance at one end to 10 produce the enlarged section *h*'. Again, a roll of gradually increasing diameter, as *i*, Fig. 4, may be positioned with its greater diameter adjacent to the longitudinal guide of the delivery table to secure the increased 15 tractive effect for the sheets as they are successively placed thereon.

It will be appreciated that the delivery table supplied with my improvements, as herein claimed, may thus be rendered more 20 efficient in advancing the sheets of paper, while avoiding the disadvantage of unequally presenting said sheets in indeterminate angular relation to the associated mechanism. By adopting these for any of 25 the delivery tables of this class the accuracy of handling the sheets thereon is readily controllable and invariably improved.

As a specific example of dimensioning the rollers for a delivery table in accordance with my invention, I may instance the 30 enlargement of rollers having a normal diameter of $1\frac{5}{16}$ inches throughout the major portion of their length to an added diameter of from one-eighth to three-sixteenths 35 inches throughout a section of approximately two to two and one-half inches at one end thereof.

If desired, the enlargement of the rollers may be accomplished by building up a short 40 section of adhesive tape, or an adhesive material may be applied sectionally thereto; the inherent principle of my invention being the production of a driving surface upon the roll or rolls which shall be more 45 effective than is the major portion of such roll or rolls.

Having now described one embodiment of my invention and the mode of its opera-

tion, I claim as new and desire to secure by Letters Patent, together with such modifications as may be made by those ordinarily skilled in the art, the following:

1. A sheet conveyer mechanism comprising a plurality of parallel rollers together forming an advancing surface for 55 the sheets, means for rotating said rollers in unison, an associated lateral guide; said rollers being terminally constructed to afford an increased tractive effect adjacent to the guide as compared with the bodies of 60 the rollers, substantially as set forth.

2. As a new article of manufacture, a roller for delivery tables of the class described having a terminal cylindrical portion thereof formed of greater uniform diameter than the body of said roller, substantially as set forth.

3. As a new article of manufacture, a roller for delivery tables of the class described terminally provided with means affording an increased driving effect throughout a short cylindrical section of one end as compared with the entire roller and its opposite end, substantially as set forth.

4. A delivery table of the class described, 75 comprising a plurality of diagonally positioned rollers, means for driving said rollers and a lateral guide associated with the corresponding ends of the rollers; said rollers being equipped with means for increasing 80 their tractive effect adjacent to the guide, substantially as set forth.

5. In a delivery table of the class described, the combination with a plurality of advancing rollers whereon the sheets 85 normally are carried, means for rotating them in unison, a guide adjacent to the corresponding ends of the rollers; said rollers having increased diameters adjacent to the guide as compared with their diameters at 90 their opposite ends, substantially as set forth.

In testimony whereof he affixes his signature.

RAYMOND S. DALTON.
